SOUND RECORDING METHOD AND SYSTEM

Frederick George Albin, Los Angeles, Calif., assignor to Radio Corporation of America, a corporation of Delaware

Application December 31, 1942, Serial No. 470,886

10 Claims. (Cl. 179—100.3)

This invention relates to sound recording apparatus, and particularly to a system in which the light source itself is the modulating element.

There are several types of sound recording systems known in the art, some of which employ constant light sources wherein the light beam is vibrated by mechanical elements such as light valves or galvanometer mirrors, and others of which employ variable intensity vapor or glow lamps wherein the intensity thereof is varied in accordance with the sound waves being recorded. The present invention is directed to a system of the latter type wherein the light may be modulated by the displacement of the light emitting element as well as by varying its intensity.

The system therefore has many of the advantages of the glow lamp combined with the advantages of the systems using constant intensity light sources. The system is also adaptable for recording a combination record wherein the average intensity is varied for noise reduction or volume control purposes, and the instantaneous values are varied for recording the sound signal itself, as is disclosed in Kreuzer Patent No. 2,357,665 of September 5, 1944.

Some of the advantages of the present system are the elimination of mechanical motion which avoids mechanical resonance and transient effects. Due to the lack of inertia, the distortion is low at all frequencies and levels, while an abundance of light is provided. The system is rugged and safe from overload damage, is relatively inexpensive and can produce a squeeze track effect.

The principal object of the invention, therefore, is to improve on present methods of and means for sound recording.

Another object of the invention is to provide an improved light modulated sound recording system.

A further object of the invention is to provide a sound recording system wherein the light emitting element is displaced in accordance with the sound waves being recorded.

A further object of the invention is to provide a sound recording system wherein the light source may be simultaneously modulated in intensity and displacement.

A further object of the invention is to provide a glow lamp type of recording system wherein light modulation is obtained by magnetically varying the position of the light source.

Although the novel features which are believed to be characteristic of this invention are pointed out with particularity in the claims appended

herewith, the manner of its organization and the mode of its operation will be better understood by referring to the following description, read in conjunction with the accompanying drawings, in which:

Fig. 1 is a diagrammatic view of a sound recording system embodying the invention.

Fig. 2 is a detailed cross-sectional view of the light source used in the invention.

Fig. 3 is a graph showing the variation between the light intensity at different distances from the center line of the arc stream.

Figs. 4 and 5 are detailed views of different types of light slits used in the invention.

Fig. 6 is a detailed view of a modification of the optical portion of the invention, and

Fig. 7 is a detailed view of another method of modulating the light source in accordance with the invention.

Referring now to Fig. 1, a capillary mercury vapor lamp is shown at 5 which may be any well-known type, such as an Hanovia AH-8. In Fig. 2, the lamp 5 is shown with transparent wall section 6 and terminal electrodes 7 and 8 between which the arc stream 16 is produced. Surrounding the lamp is a magnetic yoke 10 having two similar polarized poles at 11 and 12, and a pole 13 of opposite polarity. This magnetic yoke is polarized by current passing through a winding 15 which produces a magnetic flux at right angles to the arc stream 16. Variations in the magnetic flux in which the arc is located, caused by varying currents in the winding 15, will produce a movement or displacement of the arc stream 16 from top to bottom of the drawing. The two pole pieces 11 and 12 are so arranged as to form an aperture through which light from the arc stream passes for use in recording on a film 25.

The light passing the yoke aperture is projected by a lens 20 and a lens 21, to a slit mask 22 having a slit 23 therein. The light passing the slit 23 is projected to the film 25 by objective lenses 26, after passing the partially silvered or dichroic reflector 27, such a reflector being disclosed in

Collins Patent No. 2,274,530 of February 24, 1942. The slit 23 is imaged by the lenses 26 on the film 25, thus providing a sharp image thereon. The shaded portion between slit 23 and film 25 represents an absence of light over approximately one-half of the image of the slit 23 on the film when the arc stream 16 is in the position shown in Fig. 1.

The remainder of the recording system shown in Fig. 1 includes a microphone 29 feeding a pre-amplifier 30 which is connected to a power am-

plifier 31, the output of the latter being impressed on the magnetic field winding 15 for modulating the arc 16. Since a certain non-linearity of response is inherent in such a vapor lamp, a feedback circuit is provided which includes a photocell 33, which receives light through a lens 34 from the reflector 27, and a feedback amplifier 36, the output of which is connected to amplifier 31. This feedback circuit provides linearity over the operating level range of the recording system and may be of any suitable type, such as shown in Singer Patent No. 2,292,166 of August 4, 1942; Balsley Patent No. 2,242,638 of May 20, 1941; or in copending applications, Ser. No. 470,663, filed December 30, 1942; Ser. No. 467,442, filed November 30, 1942; Ser. No. 485,255, filed April 30, 1943; and Ser. No. 485,256, filed April 30, 1943.

To produce a variable density sound record on the film 28, the arc stream 16 is moved transversely across the aperture between the poles 11 and 12 in accordance with the amplitude and frequency of the signal being recorded. The image on the film 28 may be either solely a variable intensity image of constant width as shown in the arrangement of Fig. 1, or a variable width image in accordance with the shape of the slit masks, it being understood that a push-pull system may also be provided, in accordance with my co-pending application, Serial No. 447,797, filed June 20, 1942. The arc stream may also be displaced and modulated electrostatically by using charged plates on opposite sides of the arc as is well known in cathode ray tube practice.

The slit 23 or the aperture between poles 11 and 12, may be either large or small as compared with the arc stream width, Fig. 3 showing two slit widths superimposed upon a curve showing the intensity of the arc stream at varying distances from the center line of the arc. For instance, at zero distance, the arc is considered to have a 100% intensity, the intensity decreasing equally on both sides thereof as the distance from its center line increases, the arc having an intensity of approximately 5% at a distance of 100 mils. Now, assuming that the aperture employed is of the width of aperture "A" or approximately 10 mils, the amount of light reaching the film may be considered as represented by the area between the dotted aperture lines and the solid intensity line. As the dotted lines are moved horizontally across the paper it will be noted that the included area will change, increasing toward the right and decreasing toward the left. Such a width aperture will produce a variable density record of high resolution and having a certain illumination efficiency. To increase the illumination efficiency an aperture of the width shown by aperture "B" may be employed wherein the aperture is in the neighborhood of 100 mils wide, this width aperture giving a lower resolution than aperture "A." Intermediate width apertures may also be employed, the narrower the aperture the higher the resolution and the lower the illumination efficiency for a given intensity arc.

To further illustrate the manner of modulation of the light with the two different sized apertures "A" and "B," reference is made to Figs. 4 and 5 wherein may be observed the height of the apertures "A" and "B" with respect to the intensity gradient of the arc stream represented by the graduated shading. As the arc is displaced with respect to the slits or apertures, the effect is as though the slits were moved across the arc. Thus, in this manner varying light quanta reach the film in accordance with the arc's position. From

these figures, it will be readily seen that any movement of the arc across the apertures "A" and "B" will vary the light quanta passing therethrough, it being only necessary to displace the arc stream 16 in the neighborhood of 50 mils with aperture "A" and in the neighborhood of 100 mils with aperture "B" to vary the light between its maximum and minimum intensities, the range being greater for aperture "B."

5 A simplified method of and means for light impressing the film with variations in light quanta by arc displacements is illustrated in Fig. 6 wherein an aperture 41 is provided in a mask 40 located between the arc stream 16 and the aperture formed between the pole pieces 11 and 12. The aperture 41 is focussed on a film 44 by the lenses 42 and 43. This arrangement eliminates several of the optical elements of the system of Fig. 1 and increases the illumination efficiency but provides an image which is somewhat less sharp than that from the system of Fig. 1. With the arc 16 in the position shown the film image is illuminated at approximately one-half its maximum intensity which the shaded lines are supposed to illustrate.

20 In Fig. 7 a modification is illustrated wherein a fixed potential is applied across windings 15 from a suitable source of supply, such as a battery 48, thus providing a constant magnetic field for the arc. A similar constant field may be supplied by a permanent magnet as is done in loud speaker design. The arc in Fig. 7 is displaced or modulated by varying the current flow through the arc stream, conductors 47 and 48 being connected to the electrodes 7 and 8 as shown in Fig. 2, and to the amplifier 31 of Fig. 1 in series with an arc power supply such as a battery 49. Used in this manner, the well known type of motor action is obtained wherein the arc is displaced in accordance with the strength of the current in the arc and the strength of the magnetic field. In this embodiment the inductive effect of the winding 15 is not encountered in modulating the arc while variations in light at the film caused by both displacement and arc intensity are obtained, thus providing increased sensitivity.

25 In addition to the individual use of the two types of modulations just described, that is, magnetic deflection of the arc stream by varying the magnetic field and deflection of the arc stream by varying the current flow therethrough, it is possible to simultaneously combine the two types of modulation during the recording of a sound signal. That is, the arc may be displaced by varying the current in the arc in accordance with the instantaneous values of the sound waves being recorded as shown in Fig. 7, and the arc may be displaced by varying the strength of the magnetic field in accordance with the average value 30 of the sound waves being recorded. Thus, a form of squeeze track noise reduction may be obtained in this way. For normal noise reduction action both the signal and noise reduction currents are impressed on the same modulating means. Also, the instantaneous signal variations may be impressed on the winding 15 and the noise reduction currents impressed over conductors 47 and 48. This is also a manner of obtaining amplitude control since one of the modulating means may be varied in accordance with level cues, either manually or automatically to provide a record such as shown in the above-identified application, Serial No. 424,780.

35 It will be observed that the modulating elements do not include any mechanically moving

parts, which fact avoids resonance and other well known disadvantages of mechanical systems. The type of modulation is safe against overload damage and is relatively inexpensive as compared with certain other types of mechanical modulators. Since the modulating element has a minimum of inertia, low distortion at all frequencies and levels is obtained, while linearity is obtained through inverse feedback. Since a mercury vapor lamp is employed, an abundance of light is provided suitable for recording on fine grain film, particularly if large apertures such as aperture "B" of Figs. 3 and 5 are employed. Furthermore, a fundamental fault of gaseous lamp modulation, namely, gas ionization lag or inertia, is avoided. Arc displacement modulation also avoids a further fault of intensity modulation of gaseous lamps, particularly serious when noise reduction is employed, such as the change of ambient temperature due to change of average lamp current, since with arc displacement modulation the average current, thence the ambient temperature remains constant at all times.

I claim as my invention:

1. A sound recording system comprising a gaseous light source, means for positioning said source in a magnetic field, an optical system for projecting light from said source to light sensitive material, and means for varying said magnetic field in accordance with sound waves to be recorded, said light source being displaced in accordance with said variations in magnetic field to vary the light impressed on said light sensitive material.

2. A sound recording system comprising a substantially inertialess light source, means for positioning said source in a magnetic field, an optical system for projecting light from said source to light sensitive material, and means for varying said magnetic field in accordance with sound waves to be recorded, said light source being displaced in accordance with said variations in magnetic field to vary the light impressed on said light sensitive material, the intensity of said light source being graduated away from its center, displacement of said source in one direction causing lower light intensities to be impressed on said light sensitive material and displacement of said source in the opposite direction causing higher light intensities to be impressed on said material.

3. A sound recording system in accordance with claim 1 in which said light source is displaced in accordance with both the instantaneous values and the average value of said sound waves to be recorded.

4. A sound recording system comprising means for generating electrical currents corresponding to sound waves to be recorded, a gaseous light producing element, means for positioning said element in a magnetic field of constant strength, an amplifier for said currents, means for connecting said amplifier to said light producing element, a film and an optical system for projecting light from said element to said film, variations of said

electrical currents varying both the intensity and position of said element in said magnetic field to vary the quanta of light impressed on said film.

5. A sound recording system comprising means for generating electrical currents corresponding to sound waves to be recorded, a substantially inertialess light producing element, means for positioning said element in a magnetic field of constant strength, an amplifier for said currents, means for connecting said amplifier to said light producing element, a film and an optical system for projecting light from said element to said film, variations of said electrical currents varying both the intensity and position of said element in said magnetic field to vary the quanta of light impressed on said film, an aperture being provided in said optical system, the width of said aperture controlling the frequency resolution of said light variations with respect to the illumination efficiency of said element.

6. The method of recording a variable density photographic sound record comprising generating light waves with a substantially inertialess source, projecting said light waves in a predetermined shape to a light sensitive material, and varying the intensity and displacement of said source of light waves in accordance with sound waves to vary the intensity of said light waves as impressed on said material.

7. The method in accordance with claim 6 in which said source of light waves have a graduated intensity and are displaced magnetically.

8. The method of recording a variable density photographic sound record comprising generating a beam of light waves graduated in intensity in two directions, projecting a portion of said light waves to a light sensitive material, and magnetically displacing said generated beam in accordance with sound waves to be recorded to project different portions of said generated beam to said material.

9. The method of recording a variable density photographic sound record comprising generating a light beam having a graduated intensity, generating electrical currents corresponding to sound waves to be recorded, projecting a portion of said beam to light sensitive material, and varying the intensity of generation of said light beam to vary the intensity of the portion of said beam projected to said material, said variation in intensity also varying the particular portion of said beam so projected.

10. A sound system comprising a source of light waves, a film, means for projecting said light waves to said film, means for generating a magnetic field, said source being positioned therein, means for generating electrical currents corresponding to the instantaneous values of sound waves to be recorded, said currents being impressed on said light source, and means for generating electrical currents for varying said magnetic field to displace said light source.

FREDERICK GEORGE ALBIN.
